TAP SOLE

Application filed July 9, 1930. Serial No. 466,631.

This invention relates to shoes for tap dancing, and to a tap sole to be attached thereto.

To aid the production of sound in tap dancing, it is customary to attach a tap sole, ordinarily in the form of a metallic plate, to the sole of the shoe of the dancer. If such a plate is localized to the extreme toe portion of the shoe it does not interfere with the bending of the shoe, but it then is only possible to tap the shoe at its tip. If, on the other hand, the tap sole is extended to the ball of the foot, it makes the shoe rigid and prevents that flexibility which is essential to successful dancing. The primary object of the present invention is to overcome the foregoing difficulties and to provide a tap sole which will not appreciably diminish the flexibility of the shoe when attached thereto.

I have found that tap soles heretofore used were relatively unscientifically designed, because insufficient consideration was given to the nature of the tap dancing for which they were used. Investigation shows that considerable tapping is done with the inner edge of the foot. This is so because the weight of the dancer is rested upon one foot, while the other foot is used for tapping. Furthermore, in most steps the feet are spaced apart while dancing, and in such steps the tapping is performed predominantly with the inner edges of the soles. Accordingly, it is another object of my invention to so shape a tap sole or plate that it will be advantageously usable for the tap dancing steps previously outlined, while not sacrificing the desired flexibility of the shoe.

Other objects of my invention reside in the provision of a tap sole which will be light in weight and readily attached to a shoe. To the accomplishment of the foregoing and such other objects as will hereinafter appear, my invention consists in the tap sole elements and their relation one to the other, as hereinafter are more particularly described in the specification and sought to be defined in the claims. The specification is accompanied by drawings in which:

Fig. 1 is a view looking at the bottom of a tap sole for use on a left shoe;

Fig. 2 is a side elevation of the same applied to a shoe;

Fig. 3 is a bottom view of a pair of shoes provided with tap soles embodying my invention; and

Fig. 4 is a section taken in the plane of the line 4—4 in Fig. 1.

Referring to the drawings, the tap sole 12 comprises a toe portion 14 and a marginal or wing portion 16 extending rearwardly from the toe portion along only the inner edge of the sole. Differently expressed, the tap sole 12 is shaped to fit the toe of the shoe 20, but one side edge, preferably the inner side edge of the tap sole, extends toward the rear of the shoe a substantial distance further than the other or opposite side edge of the tap sole. I have found that in spite of the rigidity of the tap sole, bending of the shoe is readily permitted if the tap sole is extended backward from the tip of the shoe along only the inner edge of the shoe instead of across the entire width of the shoe. This is true even though the marginal or wing portion of the plate of the tap sole is extended rearwardly to a point in the region of the ball of the foot.

The described construction is exceedingly advantageous because it permits bending of the shoe and at the same time facilitates tapping with the inner edge of the shoe, and, as was above explained, most of the tap dancing steps are performed by tapping with the inner edge of the shoe sole, due to the fact that the weight is rested on the foot which is not tapping, and the feet are ordinarily spaced apart.

My invention possesses the further advantage of reducing the area of the tap sole and consequently lightening the same. This desirable result is carried further by making the tap sole out of a light metal such as aluminum or alloys thereof. The tap sole is preferably, though not necessarily, cast, and the outer surface may be made slightly convex and is carefully rounded at all of the exposed edges in order not to impede the dancing and tapping of the feet.

The tap sole is preferably further lightened by making the inner surface hollow. The hollow portion is indicated by the dotted

line 18 in Fig. 1 and is best shown in the section given in Fig. 4.

A suitable number of holes 22 are distributed about the periphery of the tap sole, through which suitable nails or screws may be driven to attach the tap sole to the sole of the shoe. These holes are preferably countersunk, as is clearly indicated in Fig. 1, so that the heads of the nails or screws will not project from the smooth finished surface of the tap sole.

The mode of constructing and applying my invention, and the advantages thereof, will be apparent from the foregoing description thereof. It will be apparent that while I have shown and described my invention in the preferred form, many changes and modifications may be made in the structure disclosed without departing from the spirit of the invention, defined in the following claims.

I claim:

1. A tap sole for attachment to a dancing shoe comprising a rigid metal plate shaped to fit and cover the sole area at the toe portion of the shoe, the forward edge of said plate being curved to approximately follow the contour of the toe portion of the shoe, the rear edge of said plate extending generally transversely of the shoe, and the said edges defining an enclosed or solidly filled-in area of metal, one outside edge of said plate extending into the ball portion of the shoe, and extending toward the rear of the shoe, when attached thereto, a substantial distance further than the opposite outside edge of said plate, in order to permit bending of the shoe at the toe portion thereof, while permitting tapping with the edge of the foot.

2. A tap sole for dancers comprising a cast aluminum plate having a toe portion and a relatively narrow wing portion projecting rearwardly from the toe portion, along only the edge of the plate which lies along the inner side edge of the shoe when the plate is attached thereto, to a point in the region of the ball of the foot, said plate having a slightly convex outer surface, a hollowed inner surface, and a plurality of countersunk holes distributed about the periphery thereof for attaching the same to the sole of a shoe.

3. In combination, a dancing shoe, and a tap sole attached thereto comprising an aluminum plate having a toe portion and a relatively narrow wing portion extending rearwardly from the toe portion along only the inner side edge of the sole of the shoe to a point in the region of the ball of the foot, said plate having a slightly convex outer surface, a hollowed inner surface, and a plurality of attaching means distributed about the periphery thereof by means of which it is fastened to the sole of the shoe.

4. A tap sole for tap dancers comprising a metal plate having a toe portion and a wing portion formed integrally therewith; said toe portion defining an enclosed or filled-in approximately semicircular area the curved forward edge of which approximately follows the contour of the toe portion of the shoe, and the rear edge of which extends transversely of the shoe; and the said wing portion extending rearwardly from the toe portion along one edge only of the tap sole.

5. A tap sole for tap dancers comprising a rigid cast metal plate having a toe portion and a wing portion formed integrally therewith; said toe portion defining an enclosed or filled-in approximately semicircular area the curved forward edge of which approximately follows the contour of the toe portion of the shoe, and the rear edge of which extends transversely of the shoe; and the said wing portion extending rearwardly from the toe portion along one edge only of the tap sole.

6. A tap sole for tap dancers comprising a rigid aluminum plate having a toe portion and a wing portion formed integrally therewith; said toe portion defining an enclosed or filled-in approximately semicircular area the curved forward edge of which approximately follows the contour of the toe portion of the shoe, and the rear edge of which extends transversely of the shoe; and the said wing portion extending rearwardly from the toe portion along one edge only of the tap sole.

7. A tap sole for tap dancers comprising a metal plate having a toe portion and a wing portion formed integrally therewith; said toe portion defining an enclosed or filled-in approximately semicircular area the curved forward edge of which approximately follows the contour of the toe portion of the shoe, and the rear edge of which extends transversely of the shoe; the said wing portion extending rearwardly from the toe portion along one edge only of the tap sole; said tap sole being slightly convex on its outer or lower face, and hollowed out or concave on its inner or upper face.

8. A tap sole for attachment to a dancing shoe, comprising a rigid metal plate shaped to fit and cover the sole area at the toe portion of the shoe, the forward edge of said plate being curved to approximately follow the contour of the toe portion of the shoe, the rear edge of said plate extending generally transversely of the shoe, and the said edges defining an enclosed or solidly filled-in area of metal, one outside edge of said plate extending toward the rear of the shoe, when attached thereto, a substantial distance further than the opposite outside edge of said plate, in order to permit bending of the shoe at the toe portion thereof, while permitting tapping with the edge of the foot, said tap

sole plate being slightly convex on its outer or lower face, and hollowed out or concave on its inner or upper face.

Signed at New York city in the county of
New York and State of New York this 7th
day of July, A. D. 1930.
